UNITED STATES PATENT OFFICE.

GEORGE HENRY WHEARY, OF RACINE, WISCONSIN.

TRUNK-FIXTURE.

1,401,219.

Specification of Letters Patent. Patented Dec. 27, 1921.

Application filed November 5, 1917. Serial No. 200,292.

To all whom it may concern:

Be it known that I, GEORGE HENRY WHEARY, a citizen of the United States, and resident of Racine, in the county of Racine and State of Wisconsin, have invented new and useful Improvements in Trunk-Fixtures, of which the following is a description, reference being had to the accompanying drawings, which are a part of this specification.

10 This invention relates to improvements in trunk fixtures more particularly, although not solely, adapted for use in wardrobe trunks having closed wardrobe section ends.

15 Many wardrobe trunks now on the market have closed wardrobe section ends and in removing or draping garments over the garment hangers mounted on the tracks of the trunk it is necessary to withdraw the hangers from the wardrobe section. In the present construction of trunk fixtures the hangers cannot be conveniently withdrawn and particularly when garments are draped thereon.

20 It is one of the objects of the present invention to overcome the before mentioned objectionable features and provide a trunk fixture in which the extensible ends of the tracks may be swung out of the wardrobe section of the trunk and firmly maintained in extended position by a means which will also withdraw the hangers from the trunk section.

25 A further object of the invention is to provide a trunk fixture having means for automatically locking the extensible track ends in folded position.

30 A further object of the invention is to provide a trunk fixture in which the extensible track ends cannot be swung to folded position until the garment hangers have been slid into the trunk section, and when so moved will be automatically maintained in position within the trunk section.

35 A further object of the invention is to provide a trunk fixture which is of simple construction, is strong and durable and is well adapted for the purpose described.

40 With the above and other objects in view the invention consists of the improved trunk fixture and its parts and combinations as set forth in the claims, and all equivalents thereof.

45 In the accompanying drawing in which

the same reference characters indicate the same parts in all of the views:

55 Figure 1 is a front view of the upper portion of a wardrobe section of a trunk showing the improved trunk fixture mounted therein and in extended position;

Fig. 2 is a vertical sectional view thereof taken on line 2—2 of Fig. 1;

Fig. 3 is a similar view with the extensible track ends shown in folded position;

Fig. 4 is a sectional detail view taken on line 4—4 of Fig. 3;

Fig. 5 is a top detail view with a portion of the telescoping member broken away to show the hinge of the track members; and

Fig. 6 is a sectional detail view taken on line 6—6 of Fig. 3.

Referring to the drawing the numeral 8 indicates the upper portion of the wardrobe section of a wardrobe trunk of the closed top type having the improved trunk fixture 9 mounted therein. The improved fixture 75 9 comprises a rear bar or member 10 securely fastened to the upper portion of the back of the trunk section and has connected thereto fixed parallel tracks 11 which project forwardly therefrom in spaced relation adjacent the side walls of the trunk section. The forward end portions of the fixed tracks are provided with and supported by downwardly extending angular brackets 12 which are connected to side walls of the trunk section. Downwardly foldable extensible tracks 80 13 are hinged to the outer ends of the fixed tracks 9 as indicated by the numeral 14 and at their outer end portions are formed with tubular enlargements 15 and projecting stop 85 knobs 16. The hinge portions 14 are constructed to form a smooth flush connection between the parts to permit the tubular hanger-carrying members 17 to freely slide thereover. The said tubular members are 90 formed with longitudinally extending elongated slots 17' on their lower sides and are slidably mounted on the fixed tracks and correspond approximately to the length of said tracks and are adapted to support the 100 two point suspension hangers 18 thereon having opposite hooked end portions 18' which hook over the tubular members.

105 Said tubular members 17 are provided at their rear ends with upstanding fingers 19 and at their forward ends with downwardly

extending fingers or handles 20 having spring locking members 21 connected to and projecting forwardly therefrom. The brackets 12 extend through the elongated slots 17' 5 and said slots permit the sliding movement of the tubular members with relation to the fixed brackets.

The distance between the hinge connection 14 and the inner edge of the tubular 10 enlargement 15 of each extensible track is less than the length of each tubular hanger supporting member 17 so that when the extensible tracks are swung upwardly and the tubular members are pulled outwardly to 15 their limit of travel as shown in Fig. 2 the hinge joints will be overlapped by the tubular supporting members and the extensible tracks will be maintained in extended or open position. The tubular supporting members 20 are pulled outwardly by means of the downwardly extending handles or fingers 20 and in pulling out the members the upstanding fingers 19 will cause the garment hangers 18 resting on the members and garments 25 which may be draped over the hangers to be withdrawn with the members from the wardrobe section of the trunk to a position of convenient accessibility outside of the section. When the tubular supporting members 30 are in their outer positions some of the garment hangers may be moved forwardly to rest upon the tubular enlargements of the extensible tracks and thus provide greater space between the hangers to remove or replace garments on the hangers. 35

In sliding the tubular supporting members and the hangers mounted thereon into the wardrobe section the extensible tracks will automatically swing downwardly by gravity 40 and will snap into locking engagement with and between the spring members 21 and be yieldingly maintained in said position. As the garments draped over the hangers will project sidewise beyond the opposite ends 45 of the hangers the extensible tracks will also serve to hold them in position.

From the foregoing description it will be

seen that the trunk fixture is of very simple construction and is well adapted for the purpose desired.

50

What I claim as my invention is:

1. A trunk fixture, comprising spaced parallel fixed tracks having means for connecting their rear end portions to the rear portion of a trunk section and also having 55 downwardly extending brackets for connecting their outer end portions to the sides of the trunk section, extensible track members hinged to the outer end portions of the fixed tracks and movable from angular positions to 60 positions in alinement with their respective fixed tracks, slotted tubular members slidably mounted respectively on the fixed tracks and movable outwardly therefrom to telescope the hinges and portions of the extensible 65 tracks, the brackets extending through the slots of the tubular members and the said tubular members having rear end projecting portions for positively causing garment 70 hangers suspended on the tubular members 75 to move therewith, and also having downwardly projecting handle fingers for moving the tubular members inwardly or outwardly, said handle fingers having means for yieldingly maintaining the extensible tracks in angular position with relation to the fixed tracks.

75

2. A trunk fixture, comprising a fixed horizontal track member, an extensible track member hinged to the outer end thereof and movable to a position in alinement therewith, and a tubular member slidably mounted on the fixed track member and movable outwardly therefrom to maintain the extensible track in extended alined position, 80 said tubular member having a rear end outwardly projecting portion for causing garment hangers mounted thereon to move therewith and also having at its forward end a downwardly extending handle finger 85 provided with yielding means for holding the extensible track in angular position.

80

In testimony whereof, I affix my signature.

GEORGE HENRY WHEARY.
